UNITED STATES PATENT OFFICE

2,327,286

CHAIR GLIDER

Abe Oslick, Philadelphia, Pa.

Application November 18, 1939, Serial No. 305,157

3 Claims. (Cl. 155—65)

This invention relates to chair gliders, particularly to the smaller kind thereof which are adapted for the use of children.

One of the objects of my invention is to produce a chair glider which can be easily entered and easily operated, and one that will be safe for a child to use.

Another of the objects of this invention is to provide in a glider of the class described, operable members having handles, conveniently located for operation, by the child.

Another object is to provide with the said chair glider a detachable shelf, positioned to be in front of a child sitting in the chair.

A further object of my invention is to provide a double swinging chair glider having each chair part thereof fulfil the above named objects, besides having the chairs so arranged, on the glider that children sitting therein, will face one another, when the glider is operated.

With these and other objects, which will hereinafter appear, my invention resides particularly in the mechanism for manually operating the chair glider, by the one sitting therein.

In the drawings,

Figure 1 is an elevation of a form of single-chair glider with mechanism embodying my invention.

Figure 2 is a top plan of the glider, shown in Figure 1.

Figure 3 is a perspective view of lower front, swinging part of the glider, shown in Figures 1 and 2.

Figure 4 is a perspective view showing the main operating parts of the glider, journaled with the stationary bottom runners.

Figure 5 is a perspective view of the tray or shelf, having projecting, flat bars, adapted for sliding engagement with the slotted arms of the chair part of the glider, shown in Figures 1 and 2.

Figure 6 is an elevation of a double chair glider, embodying my invention.

Figure 7 is a top plan of the double chair glider shown in Figure 6.

Figure 8 is a rear end, elevation of the double chair glider shown in Figures 6 and 7, as well as of the single chair glider shown in Figures 1 and 2.

Figure 9 is a fragmental, inverted perspective view of a shelf supported on the two chairs of the double glider.

In the figures, referring particularly to the single chair glider shown in Figures 1—5, inclusive, the bottom runners 10 and 11 are held in spaced relation by being fixed to the two cross members 12 and 13. Upstanding from the runner 10, 55

and fixed thereto, are the two posts 14 and 15, and upstanding from the runner 11 and fixed to it are the two posts 16 and 17. Between these side pairs of upstanding posts is suspended the single chair rocker 18 of the glider. A foot platform is formed by cross slats 19, fixed on top of the parallel chair rocker beams 20 and 21. Upstanding integrally from the beams 20 and 21 are the upright, front, chair members 22 and 23, forming the front legs of a chair 24. The inclined back frame part 25 of the chair has parts forming the legs 26 and 27, which are fixed to the horizontal beams 20 and 21 respectively. 28 is the seat of the chair 24, and 29 and 30 are respectively, the horizontal, chair arms, fixed to the upright members 22 and 23. Two suspending loops 31 and 32 support the chair rocker 18, to hang from the top parts of the posts. The bottom cross part of the loop 31 engages the under notches 33 and 34, in the rear parts of the respective beams 20 and 21, and the loop 32 engages the under notches 35 and 36 in the front part of the respective beams 20 and 21. The top ends 37 and 38 of the loop 31 are bent horizontally outward, to engage the respective holes 39 and 40, in the upper ends of the posts 14 and 16. The top ends 37a and 38a of the loop 32 are also bent horizontally outward, to engage the respective holes 39a and 40a, in the upper ends of the posts 15 and 17. The outer ends of the holes 39, 39a, and 40 and 40a are each covered with a sheet metal cap 41.

The operating mechanism of the glider has two, outwardly bent, upright, lever bars 42 and 43, 35 which terminate above in the respective handles 44 and 45. These upright bars 42 and 43 are journaled upon the respective bolts 46 and 47, in the upper forward part of the chair 24, on the respective upright members 22 and 23 of the chair 24.

A round and bent cross bar 48, journaled in holes 49 and 50, in the respective runners 10 and 11 serves to locate, in swinging relation, the engaged, upright lever bars 42 and 43. The cross-bar 48 is formed to have two V-lever portions 51 and 52, connected integrally by the cross-portion 53. Each V-lever portion has a long leg 54, and a short leg 55, which come together at 56, where they pass through holes 57b and 57c, in the lower ends of the lever bars 42 and 43. The cross-portion 53 of the cross bar 48 is positioned below the plane common to the long legs 54, for spaced freedom, below the chair member beams 20 and 21.

58 is a shelf having fixed thereto two extending, thin bars 59 and 60. Each of these bars has spaced notches 61 and 62, and each of these

bars is adapted for releasable sliding engagement with the longitudinal channels 63 and 64, in the respective chair arms 29 and 30, and the notches 61 and 62, in the bars 59 and 60, are adapted for releasably engaging the cross pins 65, in the respective chair arms 29 and 30.

Referring now to the double-chair glider, shown in Figures 6, 7 and 8, the bottom runners 66 and 67 are held in spaced relation by the cross-members 68 and 69 fixed thereto. Upstanding integrally from the runner 66 are the two posts 70 and 71, and upstanding integrally from the runner 67 are the two posts 72 and 73. Between the side pairs of upstanding posts is suspended the double chair rocker 74, having beams 75 and 76, upon which are integrally mounted the two chairs 77 and 78 spaced and so positioned that their rear parts are at the ends of the glider.

The chair 77 has two upright front members 79 and 80 fixed to the respective beams 75 and 76, integrally supporting the horizontal arms 81 and 82 of the chair 77. This chair 77 has a back frame 83, to which is fixed the arms 81 and 82, the beams 75 and 76, and the seat 84, which is also fixed to the upright front members 79 and 80. The chair 78 has two upright front members 85 and 86 fixed to the respective beams 75 and 76, and integrally support the horizontal arms 87 and 88 of the chair 78, which has a back frame 89, to which are fixed the arms 87 and 88, together with the beams 75 and 76, and the seat 90, which is also fixed to the upright front members 85 and 86. A foot platform, between the chairs 77 and 78, is formed by the cross slats 91 fixed to the beams 75 and 76.

Two suspending loops 92 and 93 support the double chair rocker 74, to hang from the top parts of the posts of this double chair glider. The bottom cross part of the loop 92 engages the under notches 94 and 95, in the rear parts, of the respective beams 75 and 76, and the loop 93 engages the under notches 96 and 97 in the forward parts of the respective beams 75 and 76. The top ends 98 and 99 of the loop 92 are bent, horizontally outward, to engage the respective holes 100 and 101 in the respective posts 70 and 72, and the top ends 102 and 103 of the loop 93 are bent horizontally outward to engage the respective holes 104 and 105 in the respective posts 71 and 73.

Resting releasably upon the ends of the chair arms 81, 82, 87 and 88 is the tray or shelf 106, having fixed on the under side of each corner an L-block 107, shown in the inverted view in Figure 9.

An independent operating mechanism is provided for the use of an occupant of either of the chairs 77 or 78, but these mechanisms operate in unison. Considering the operating mechanism to be used by an occupant of chair 77, two outwardly bent lever bars 108 and 109 with the respective handles 110 and 111 are journaled upon the respective bolts 112 and 113, fixed in the upper parts of the chair members 79 and 80. A round and bent cross bar 114 journaled in holes 115 and 116 in the respective runners 66 and 67 serves to locate, in swinging relation, the engaged, upright lever bars 108 and 109. The cross bar 114 is formed like the bar 48, shown in Figure 4, and has two V-lever portions 117 and 118 connected integrally by the cross portion 119. Each V-lever portion has a long leg 120 and a short leg 121, which come together where they pass through holes in the lower ends of the lever bars

108 and 109. The cross portion 119 of the cross bar 114 is positioned to be below the plane common to the long legs 120, for spaced freedom of action, below the beams 75 and 76, the construction being similar to that shown in Figure 4, for the single chair glider. The mechanism adapted for the use of an occupant of the other chair 78 is similar to that described for the use of an occupant of chair 77, but the cross bar connected with the upright lever bars is turned, horizontally, in the opposite direction. This later mechanism includes two outwardly bent, upright lever bars 122 and 123, with top handles 124 and 125, respectively. These bars 122 and 123 are journaled upon the respective bolts 126 and 127 fixed in the upper parts of the chair members 85 and 86.

A round and bent cross bar 128, journaled in holes 129 and 130, in the respective runners 66 and 67, serves to locate, in swinging relation, the engaged, upright lever bars 122 and 123. The cross bar 128 is formed like the bars 48 and 114 (see Figure 4 for bar 48) and has two V-lever portions 131 and 132 connected integrally by the cross portion 133. Each of the V-lever portions has a long leg 134 and a short leg 135, which come together where they pass through holes in the lower ends of the lever bars 122 and 123. The cross portion 133 of the cross bar 128 is positioned to be below the plane which passes through the long legs 132, for spaced freedom of action, below the beams 75 and 76.

In operation, considering the single chair glider shown in Figures 1 and 2, an occupant in the chair 24 takes hold of the handle 44 with the right hand and takes hold of the handle 45 with the left hand and pulling back on these handles 44 and 45 the upright lever bars 42 and 43 rock back to some relative angular positions as 42a and 43a, while their lower ends are horizontally held by the cross bar 48, yet free to rock up or down therewith, the cross bar 48 being adapted to swing up or down on the pivot holes 49 and 50 in the stationary bottom runners 10 and 11. As the lever bars 42 and 43 swing backward, pivoted upon the bolts 46 and 47, fixed in the upper part of the chair 25, the chair moves backward, swinging with the loops 31 and 32, which correspondingly are then in the relative positions 31a and 32a, with the beams 20 and 21 coming up a little to the relative positions 20a and 21a. Pushing on the handles causes the lever bars 42 and 43 to swing in the opposite direction moving the chair 25 forward. Alternately pulling and pushing on the handles keeps the chair rocker 24 rocking back and forth as it hangs on the loops 31 and 32. After thus swinging the chair 25 back and forth, the occupant can readily stop this swinging by resisting the automatic tilting of the handles 44 and 45 in either direction.

Considering the operation of the double chair glider, with an occupant sitting in each of the chairs 77 and 78, referring to Figure 6, and assuming that the occupant in chair 78 pulls back on the handles 124 and 125, his chair will swing backward, with respect to himself, while the occupant in chair 77 pushes the handles 110 and 111 toward the occupant of chair 78, resulting in the double chair rocker 74 with its chairs 77 and 78, with their beams 75 and 76 passing through the respective positions 77a, 78a, 75a and 76a, of these parts. Alternate pulling and pushing on the handles by either chair occupant or together in unison, keeps the double chair rocker 74 rocking back and forth, as it hangs

on the loops 92 and 93. Resisting the movements of the handles will bring the double chair rocker to a stop. If desired, when the occupants are seated, the tray 106 can be put in place as shown in Figures 6, 7 and 8, where the L-blocks 107, at the under corners of the tray engage the sides and ends of the arms 81, 82, 83 and 84.

Considering again the chair rocker 24, shown in Figures 1, 2 and 3, when the occupant is seated in the chair 25, the tray 53 can be releasably attached by threading the notched bars 59 and 60 into the respective arm channels 63 and 64, to such a position as either the notches 61 or the notches 62 engage the cross pins 65.

It will be noted that the operating mechanism for each of the chairs 25, 71 and 78 is practically the same, therefore it is possible to have the floor runners and chair beams made longer, to accommodate the mounting of more chairs, each having practically the same operating mechanism, and swing the multiple chair rocker hanging by two loops, one near each end of the glider, hanging these loops on two sets of upright posts, located near the ends of the glider.

Other changes in construction can be made without departing from the spirit of my invention. I therefore wish to include all forms thereof which come within the spirit and scope of the following claims.

I claim:

1. In a swinging chair glider mounted to swing from the upper parts of upstanding side supports, and including a chair having a frame which includes beam members in its lower part, and chair arms in its upper part, hanging looped rods having the upper ends of the leg portions thereof pivoted in the upper parts of said upstanding supports, and having the lower portions of said rods pivoted in supporting relation with said beam members, adapting said chair to swing from the upper ends of said side supports, and manually operable means for said glider adapted to enable one sitting in said chair to swing the same back and forth upon said side supports, said means including a bar member having a U-shape with spaced arm portions connected by a cross portion beneath said chair frame, the ends of said arm portions being pivoted in the lower parts of said supports, uprightly positioned side levers pivoted near their upper ends to the upper, side, forward portions of said chair, and pivoted at their lower portions to the said cross

portion of said bar member, the said bar member being pivotally anchored in the lower part of said supports, serving to hold the lower ends of said side levers against appreciable horizontal movement, while permitting some vertical movement, so that the back and fore, angular movement, of said side levers, induced by pushing or pulling the upper ends of said side members, by one sitting in said chair, will be communicated to said chair, causing it to swing between its side supports.

2. In a swinging chair glider made in accordance with claim 1, said bar member being formed to have its leg portions include a forked shape, with the lower ends of said side levers pivoted at the crotches of said forks.

3. In a swinging chair glider having a support with upstanding side, spaced members and hanging looped rods including side leg portions pivoted at their upper ends to the upper parts of said side members and also having the lower parts of the leg portions connected by cross-portions integral therewith, a frame having spaced side beam members, crossing said leg cross-portions and supported thereon in swinging, pivotal relation thereto, a chair adjoining each of the opposite ends of said beam members and mounted on said frame, said chairs being positioned to have persons sitting therein, face one another, manually operable means to said glider connected with each of said chairs, enabling the occupant of either of said chairs to swing the same back and forth upon said upstanding members, said means including, next to each of said chairs, 30 a bar member having a U-shape with spaced arm portions connected by a cross portion beneath said chair, the ends of said arm portions being pivoted in the lower parts of said support, uprightly positioned side levers pivoted near their upper ends to the upper side, forward portions of the chair adjoining and pivoted at their lower portions to the said cross portion, of said bar member, serving to hold the lower end of said levers against appreciable horizontal movement, 40 while permitting some vertical movement, so that the back and forth angular movement of said side levers, induced by pushing or pulling the upper ends of said side levers, by one sitting in the adjoining chair, will be communicated to said 45 chair, causing it to swing.

ABE OSLICK.
